Application October 1, 1948, Serial No. 52,335
In Czechoslovakia October 9, 1947

12 Claims. (Cl. 200—148)

1

This invention relates to electric circuit breakers and, more particularly, to novel means for quenching the arc formed when the circuit breaker is opened under load.

In such circuit breakers arranged to interrupt heavy currents or high voltage circuits, provision must be made to quench the resulting arc formed between the relatively movable circuit controlling contacts. Numerous ways have already been suggested to break up and to cool the electric arcs thus shortening their duration. This can be achieved either in a gaseous medium such as air or in a liquid such as oil.

In order to obtain the arc quenching effect, electromagnetic forces acting upon the arc and/or the pressure of highly compressed air and/or the pressure of the products resulting from the decomposition of the medium surrounding the arc are utilized.

Most of the arrangements hitherto used have the drawback that the arc is continually passing through the same place, thus influencing the cooling medium and its surroundings by increasing their temperature. To overcome this drawback constructional embodiments have been suggested wherein the flow of the quenching medium is directed against movable cells arranged in the shape of a turbine runner wheel for example, whereby the arc is brought into contact with a steadily renewed, cool and electrically stable medium. In such case, however, the requirement of a high velocity of alternation of the cells must be fulfilled, involving a high velocity of the runner wheel which in turn involves certain difficulties for mechanical reasons.

The object of the present invention is the elimination of said mechanical difficulties with the maintenance of the same high cooling effect brought about upon the arc by the alternation of the cooling cells. Thus, in accordance with the present invention, instead of the runner wheel rotating at high speed, the arc proper has a high rotational speed imparted thereto. The arc control device, or runner wheel, moves at a relatively low angular velocity which is only a fraction of that of the arc proper. These results are effected by successively opening and closing the entrances to the quenching cells, surrounding the contacts, by means of a rotating arc distributing tube or timing tube functioning in the same manner as a slide valve.

The number of orifices in the timing tube differs by —1 from the number of quenching cells. Thus, if a certain cell is open, in other words, one orifice of the timing tube is aligned

2

with an orifice of a cooling cell, then in a place angularly remote by 180° the inverse situation will arise, namely a partition of the timing tube will block the entrance to another cell orifice. By suitably selecting the width of the orifices and of the partitions, both in the timing tube and in the cells, the effect may be achieved that only one cell is open while several adjacent cells are partly closed and the remaining cells totally closed, so that the gas will escape merely at one side, the arc being thus driven into that opening where there is a top speed namely into the fully open cell. As the timing tube continues to rotate, the succeeding inlet orifices of the cooling cells are successively fully opened. Due to the difference of —1 between the numbers of orifices in the timing tube and in the quenching cells, the direction of progress of full opening of successive quenching cell orifices is opposite to the direction of rotation of the timing tube. Furthermore, the speed of opening of successive quenching cell orifices is such that the orifices throughout an angle of 180° are successively opened during rotation of the timing tube through an angle subtending an arc equal in length to half the sum of the widths of one orifice and one partition. Therefore, the arc travels around the circumference of the timing tube at a speed which is a high multiple of that of the tube motion. The speed of the arc on the circumference of the tube is proportional to the linear speed of a non-rotatable mobile contact and to the pitch of a thread interconnecting the contact and the tube. A further angular displacement by the average width of a cell and partition brings about the initial state, the arc thus penetrating all cells throughout the circumference. It will be apparent that during a small angular displacement of the tube the arc travels completely around the circumference of the timing tube.

Obviously, the general arrangement may be chosen in such manner without in any way departing from the scope of the present invention that the timing tube remains stationary while the cells are rotated. It is also possible, if desired, to arrange said orifices on the circumference at different levels varying their size or width in such manner as to increase the disintegrating effect and thereby the cooling effect upon the arc.

The object of the present invention is illustrated merely by way of example in the accompanying drawing showing one constructional embodiment of my new quenching arrangement of a circuit breaker, it being understood that this embodiment is by no means exhaustive of the

possibilities of carrying into effect the basic idea of my invention.

In the drawing:

Fig. 1 is a longitudinal sectional view through a circuit breaker embodying my invention.

Fig. 2 is a somewhat diagrammatic transverse sectional view, substantially on the line x_2-x_2 of Fig. 1, illustrating the orifices and their interrelation, and

Fig. 3 is a transverse sectional view on the line x_3-x_3 of Fig. 1.

Referring to Fig. 1 the illustrated embodiment of the invention circuit breaker includes a carrier or mounting plate 1 for stationary contacts 2 engageable by a non-rotatable longitudinally movable contact 3. Such carrier 1 is mounted within an outer casing 16. Surrounding and concentric with the movable contact 3 is a control or timing tube 4 serving at the same time for admission to the interior of the circuit breaker casing. Said tube 4 is guided at its upper end by said carrier 1 and at its lower end rests firmly in a bearing 17 carried by the stationary support 9 mounted in the outer casing 16. Thus said tube 4 is secured against any other than a turning movement. The movable contact 3 is provided with a thread 5 having a large pitch and engaging a thread on the inner side of tube 4 or of the support 17 connected therewith so that any sliding movement of contact 3 effects rotation of tube 4. Blast air is introduced into tube 4 through orifices 6 provided at the circumference thereof. The partitions between said orifices 6 are arranged to reduce air losses to a minimum. The top part of the tube 4 is provided throughout its circumference with slots 7 against which the quenching cells 18 are arranged as referred to above and or shown in Fig. 2. These quenching cells 18 are surrounded by fins 8 which are made either of metal or of insulating material. The hot gases, if required may pass through additional metallic cooling fins 19 before leaving the casing 16 as indicated by the arrow in Fig. 1. In the support 9 carrying the bearing 17 of tube 4 stationary electrical contacts 10 engage the longitudinally displaceable contact 3 to provide for current flow between the electric terminals 11 and 12 when contacts 2 and 3 are engaged. Longitudinal movement of contact 3 is effected through an electrically insulated lever 13, but it will be understood that contact 3 may be operated by air pressure, or other means, in a known manner.

The main cooling air enters through an inlet pipe 14 into an inner casing 15 within the outer casing 16. A timing tube of the same design and with the same arrangement of cells may, however, be used also in oil circuit breakers. In the case of gas-generating circuit breakers where no blast air is introduced since the arc itself generates gases from the surrounding medium, it is preferable to reduce as far as possible the gap between the movable contact 3 and the timing tube 4 wherein the gases are generated, thus insuring a maximum gas generation.

In the circuit breaker described above the arc while being broken is brought into cells with a fresh ionized medium. Thus its voltage always rises rapidly after its entrance into the cell. While the arc burns inside the cell its voltage drops as the medium is being ionized.

The alternation of the medium as described before manifests itself in the course of the arc voltage curve which regularly rises and falls in

dependence on the turning movement of the control tube.

The alternating increase and decrease of the electric strength of the insulating medium and consequently of the voltage of the electric arc effects oscillations of the electric circuit into which the arc is switched through the influence of the capacity and self-induction included therein. Such oscillations occur also in any switch during breaking. In the circuit breaker according to my invention this effect is increased and the frequency of the oscillations may be controlled by changing the rate of rotation of the control or timing tube. A further increase of the oscillations of the electric circuit may be achieved by connecting a capacity or self inductance in series or in parallel with the circuit breaker. Thereby both voltage and current of the arc will be favorably influenced and conditions will be created for extinguishing the arc as a more rapid passage of the current through the zero value is attained.

While a specific embodiment of my invention has been shown and described in detail to illustrate the application of the principles thereto, it should be understood that the invention may be otherwise embodied without departing from such principles.

What I claim as my invention is:

1. In an electric circuit breaker having a fixed contact, a substantially non-rotatable movable contact cooperable with said fixed contact, and means for moving said movable contact to open and close the circuit breaker, arc quenching means comprising, in combination, a plurality of arc cooling cells arranged adjacent the junction of the contacts and having alternating arc entry orifices and cell separating partitions conjointly forming the circumference of a circle; valve means mounted for movement relative to the cell orifices and having orifice means and closing partition means successively alignable with adjacent cell orifices to open and close the same; and means operable by the movable contact to move said valve means relatively to the orifices to successively open adjacent orifices and successively close the same to direct the arc successively into adjacent orifices.

2. In an electric circuit breaker having a fixed contact, a substantially non-rotatable movable contact cooperable with said fixed contact, and means for moving said movable contact to open and close the circuit breaker, arc quenching means comprising, in combination, a plurality of arc cooling cells arranged adjacent the junction of the contacts and having alternating arc entry orifices and cell separating partitions conjointly forming the circumference of a circle substantially concentric with the direction of movement of the movable contact; rotatable valve means mounted for movement relative to the cell orifices and having orifice means and closing partition means successively alignable with adjacent cell orifices to open and close the same; and means operable by the movable contact to rotate said valve means relatively to the orifices to successively open adjacent orifices and successively close the same to direct the arc successively into adjacent orifices.

3. Arc quenching means as claimed in claim 1 in which said valve means comprises a ported cylindrical member movable to align ports therein with successive orifices.

4. Arc quenching means as claimed in claim 2 in which said valve means comprises a cylindrical member having circumferentially arranged ports.

5. Arc quenching means as claimed in claim 2 in which said valve means comprises a cylindrical member having uniformly spaced circumferentially arranged ports in the plane of the orifices, the number of ports differing from the number of orifices.

6. Arc quenching means as claimed in claim 2 in which said valve means comprises a cylindrical member having uniformly spaced circumferentially arranged ports in the plane of the orifices, the number of ports differing by one from the number of orifices.

7. Arc quenching means as claimed in claim 2 in which said valve means comprises a cylindrical member having uniformly spaced circumferentially arranged ports in the plane of the orifices, the number of ports differing by one from the number of orifices, and the circumferential spacing of said ports being greater than the circumferential widths of said ports.

8. Arc quenching means as claimed in claim 2 in which said valve means comprises a cylindrical member having uniformly spaced circumferentially arranged ports in the plane of the orifices, the number of ports differing by one from the number of orifices, and the circumferential spacing of said ports being greater than the circumferential widths of said ports and the circumferential widths of the orifices.

9. Arc quenching means as claimed in claim 2 in which said valve means comprises a cylindrical member having uniformly spaced circumfer-

tially arranged ports arranged at different levels throughout the circumference of said member, the number of ports differing by one from the number of orifices, and the circumferential spacing of said ports being greater than the circumferential widths of said ports and the circumferential widths of the orifices.

10. Arc quenching means as claimed in claim 2 in which said valve means comprises a cylindrical member having circumferentially arranged ports; and including a high pitch threaded engagement between the movable contact and said member to effect rotation of said member upon longitudinal motion of the movable contact.

15. 11. Arc quenching means as claimed in claim 2 in which said valve means comprises a cylindrical member having circumferentially arranged ports; and including means for admitting air to the interior of said member.

20. 12. Arc quenching means as claimed in claim 2 in which said valve means comprises a cylindrical member having circumferentially arranged ports; and including a high pitch threaded engagement between the movable contact and said member to effect rotation of said member upon longitudinal motion of the movable contact; and means for admitting air to the interior of said member.
